UNITED STATES PATENT OFFICE.

JOHN T. STONEY, OF LAKEWOOD, OHIO.

CLEANING APPARATUS.

Application filed April 11, 1923, Serial No. 331,301. Renewed May 11, 1925.

To all whom it may concern:

Be it known that I, JOHN T. STONEY, a citizen of the United States, and a resident of Lakewood, county of Cuyahoga, and State of Ohio, have invented a new and useful Cleaning Apparatus, of which the following is a specification.

My invention relates to apparatus adapted to clean objects or remove adherent matter therefrom by producing vibrations therein.

The main object of my invention is an efficient and simple apparatus for removing adherent matter from objects in an efficient and inexpensive manner with the least expenditure of time and labor. Other objects will appear during the description of the apparatus shown in the accompanying drawings.

Many objects, such as boxes, foundry flasks, castings, etc., have sand or other matter adhering to the walls or other parts thereof which matter must be removed. The removal of such matter has heretofore been done mostly by manual labor with a consequent expenditure of considerable time and expense.

The present invention aims to accomplish this removal of such adherent matter by means other than manual labor and thereby save considerable time and expense.

The present invention, although adapted for a wide range of applications, is illustrated, in the accompanying drawings, as one machine for carrying out my invention and as applied to an apparatus adapted to shake out the core or other sand from castings. It being understood, however, that an apparatus, embodying the features of the present invention, may be devised, with suitable modifications, to clean objects other than the casting shown or to remove adherent matter other than the sand specified, or to employ vibrator means other than that shown.

In the accompanying drawings, Fig. 1 is a plan view of an apparatus embodying the features of my invention and designed to shake out a casting; Fig. 2 is a side view of Fig. 1; Fig. 3 is a longitudinal section on a plane indicated by the line 3-3 in Fig. 1 showing the several elements more clearly; Fig. 4 is a cross section on a plane indicated by the line 4-4 in Fig. 2 showing the slide more clearly; Fig. 5 is a cross section on a

plane indicated by the line 5-5 in Fig. 2 showing the slide and the vibrator more clearly; Fig. 6 is a cross section on a plane indicated by the line 6-6 in Fig. 2 showing the bed construction under the casting more clearly; and Fig. 7 is an end view of the apparatus as viewed at 7 in Fig. 2.

Similar reference characters refer to similar parts throughout the views.

The apparatus shown in the drawings consists, principally, of the bed A, the abutment B, the movable member C, and the cylinder D.

The bed A may be made of any convenient form and height and is provided with the bars 10 upon which the casting E rests. The upper end 11 of the opening 12 in the bed A, under the bars 10, is formed as a funnel so that sand, or core wires, or other material which is shaken from the casting, may readily fall through the opening 12 and be disposed of from the bottom of the bed as by a pit, or conveyor, or other means. The bars 10 are provided as a rest for the casting E and to provide rigidity for the bed where the casting is operated upon without encumbering the opening 12 with more material than is necessary so that the shaken out material may drop through this opening 12 without undue resistance or obstruction and thereby prevent clogging of this opening.

The abutment B shown comprises the bracket 13 secured to the bed A and two abutment stools F and the spring 14 for each stool. The bracket 13 has the wall 15 which is provided with the conical opening 16. Each of the stools F is composed of the head 17 and the stem 18 which latter fits loosely in and is guided in the small end of this opening 16; due to this conical opening, the outer end of the stem 18 can move radially in all directions and thereby permit the head 17 to adjust itself automatically to uneven or beveled surfaces often found on objects to be cleaned. The springs 14 are interposed between the wall 15 and the head 17 for the purpose appearing presently. The pins 19 are provided in the stem 18 to prevent the stools F from falling out of the wall 15.

The movable member C shown comprises the slide 20 fitted to the slide-base 21 and held therein by the gibbs 22 as is usual in slide construction and one end thereof has

the upward projecting lug 23 which is provided with an opening for the pin 24. The slide-base 21 may, conveniently, be made integral with the bed A.

- 5 In the present instance, the vibrator mechanism G is secured to the slide 20 by the screws 25; this mechanism can, however, be made integral with the slide 21 with good results. The construction thereof, as a separate unit, permits of replacing this mechanism when worn without replacing the entire member.

10 The vibrator mechanism G shown consists of the housing 26 secured to the slide 20 as previously set forth and is provided with the walls 27 and 28 suitably strengthened by the ribs 29 and 30.

15 The vibrator shown, in the present instance a fluid pressure actuated vibrator, is composed of the case 31 mounted between the walls 27 and 28 and held firmly therebetween by the bolts 32; the ears 33 are provided on the case 31 to hold the same in position sidewise and also down upon its seats 34 on the housing 26. The plunger 35 fits operatively into the housing 26 and operates between the percussion plates 36 which are countersunk into the ends of the case 31 and abut on the walls 27 and 28.

20 The vibrator shown is indicative as to how a vibrator may be applied. Any sort of vibrator may be employed and mounted in such a manner that the vibrations produced therewith are effectively transmitted to the housing and subsequently to the casting. A fluid pressure vibrator, very well adapted to the cleaning apparatus shown, is shown and claimed in my pending application for vibrators, filed March 27, 1923, Serial No. 40 628,158. No claim is made for any particular vibrator in the present application.

25 The cylinder D is mounted on the wall 37 of the bracket 38 which is secured to the bed A. The piston 39 operates in the bore 40 of the cylinder D as is usual in such structures. One end of the piston rod 41 is secured to the piston 39 and extends through the stuffing box 42 and out of the cylinder where the other end thereof has the boss 43 which is provided with an opening for the pin 44.

30 A somewhat flexible connection is established between the piston rod 41 and the lug 23 by the links 45 which are located on the sides of the lug 23 and the boss 43; the elements of this structure are held together by the pins 24 and 44 as shown.

35 The jaw 46 is, in the present instance, secured to the housing 26 and is provided with the bevel face 47 adapted to engage the flange 48 of the casting E as seen in Fig. 2. This jaw may be made integral with the housing 26 although it is preferred that it be made separate as shown to the end that different jaws, adapted to different castings or

other objects, may be substituted with very little inconvenience and expense.

40 It may also be noted here that the stools F can readily be substituted by other stools adapted to objects other than the casting shown although the particular mounting of these stools shown in the drawings provides an abutment for many objects without substitution of other stools.

45 The plate 49 is secured to the end of the slide-base 21 and the spring 50 is secured thereto for the purpose appearing presently.

50 The cylinder D and the vibrator are, in the present instance, actuated by fluid pressure supplied to the three way valve 51, by the tube 52; the tube 53 leads to and supplies the vibrator with fluid pressure while the tube 54 leads to and supplies the cylinder D with fluid pressure. The exhaust and valve mechanisms of the vibrator and the cylinder are not shown in the drawings since they may be of any suitable and well known construction and the details thereof are not claimed in this application.

55 The present apparatus shown and described is distinguished from my application for "Method and apparatus for shaking out foundry flasks and the like," filed Sept. 12, 1921, Serial No. 500,193, and my Patent No. 1,447,694, March 6, 1923, for vibrator hook 90 wherein the objects to be cleaned are suspended from an overhead mechanism whereas, in the present invention, the objects are supported from below by a bed and are held thereon more rigidly than on the hook. Generally it may be noted that an object of a more solid or ribbed construction is best cleaned by holding it to the apparatus more rigidly as in the present invention whereas an object of a more flimsy construction is best cleaned by holding it to the apparatus either semi-rigidly or merely suspending the same as shown in the application and patent referred to.

60 The operation of the apparatus shown and described is as follows:—

65 Starting with the elements in the positions shown in Fig. 3 and supposing that the casting E has been shaken out and is ready for removal from the apparatus.

70 First manipulate the valve 51 to admit fluid pressure to the right hand end of the bore 40 in the cylinder D whereby the piston 39 is moved toward the left. This movement of the piston also moves the movable member C in the same direction and moves the jaw 46 away from the flange 48 of the casting E, thereby releasing the casting. When this movable member C so moves toward the left and before the left hand end of the piston reaches the wall 37, the left hand end of the movable member C abuts the free end of the spring 50 and prevents the piston from violently striking the wall 37.

The casting E is now released and can be removed from the apparatus and another casting to be cleaned is now placed on the bars 10.

5 The valve 51 is now manipulated to admit fluid pressure to the left hand end of the bore in the cylinder, thereby moving the piston 39, and consequently the movable member C and the jaw 46, toward the right 70 until the jaw 46 engages the flange 48 and pushes the casting against the stools F and against the action of the springs 14 substantially to the position shown in Figs. 1, 2, and 3. The springs 14 cushion the impact 75 of the casting on the stools and the method of mounting the stools in the wall 15 permits the heads 17 to automatically adjust themselves to the beveled surface shown on the casting.

20 When the casting abuts the stools, the jaw 46, due to the bevel face 47 thereon, holds the casting down on the bars 10 as well as against the stools F. The amount of rigidity with which the casting is held 80 25 depends upon the size of the cylinder bore and the fluid pressure. The valve 51 is arranged to retain the pressure in the left hand end of the bore and against the left hand face of the piston and thereby retain 85 30 the movable member against the casting to hold the same rigidly upon the bars 10 and between the movable member and the stools.

The valve 51 is now manipulated to admit fluid pressure to the vibrator, as is well 90 35 known in the vibrator art, thereby causing the plunger 35 to operate between and strike against the percussion plates 36 alternately.

This striking of the plunger against the 40 percussion plates produces vibrations in the housing 26 which vibrations are transmitted to the bed as well as to the bars 10 and to the jaw 46 and, in a measure, to the abutment B through the bed and the bars. 45 From these elements, the vibrations are transmitted to the casting wherein they produce certain molecular action which loosens and shakes off the sand or other material from the walls of the casting, which 50 sand or other material can readily fall down through the opening 12 from where it can readily be disposed of.

55 After the casting is shaken out, the valve 51 is manipulated to stop the vibrator and to release the fluid pressure from the left hand end of the cylinder bore and admit fluid pressure to the right hand end of the cylinder bore which again is the beginning of another operation as set forth.

60 As general remarks, applying to the particular apparatus shown and described as well as to apparatus of other forms, I have found that the abutments with the springs shown give better results than a solid abutment, not only in effective shaking out or

cleaning but also in preventing breakage of objects. The automatically adjustable stools produce better vibrations in the objects since they always bear firmly against the same which, usually, have uneven surfaces. The use of two abutment stools and one jaw acting substantially midway between them produces a better vibratory effect in the object than when they are directly opposite of each other. Any sort of vibrator may be employed as long as vibrations are produced and transmitted to the object. Any sort of holding means may be employed as long as the object is held rigidly in such a position that vibrations are produced therein by a vibrator mechanism.

Modifications, other than those pointed out, may be made; therefore, without limiting myself to the precise construction shown and described and pointed out.

I claim:—

1. A cleaning apparatus comprising, rigid means for supporting an object to be cleaned, resilient means for abutting one side of said object, and means for producing vibrations in said object.

2. A cleaning apparatus comprising, means for supporting an object to be operated upon, means for creating vibrations in said supporting means, and means for transmitting said vibrations to said object in more than one direction.

3. A cleaning apparatus comprising, a bed provided with means for supporting an object to be cleaned, resilient means for abutting one side of said object, movable means for holding said object down on said supporting means and against said resilient means, and a vibrator mechanism to produce vibrations in said bed and in said movable means.

4. A cleaning apparatus comprising, a bed adapted to receive an object to be cleaned, a resilient abutment for said object, a movable member to force said object against said abutment, a vibrator mechanism to produce vibrations in said apparatus, and means for operating said movable member.

5. A cleaning apparatus comprising, a bed adapted to receive an object to be cleaned, a resilient abutment for said object, a movable member to force said object against said abutment, a vibrator mechanism to produce vibrations in said apparatus, and means for operating said movable member; said resilient abutment comprising a wall provided with an opening, an abutment stool having a stem guided in said opening and a head on one end of this stem, and a spring over said stem and between said head and said wall.

6. A cleaning apparatus comprising, a bed adapted to receive an object to be cleaned, an automatically adjustable abutment for said object, a movable member to force said object against said abutment, a vibrator mecha-

nism to produce vibrations in said apparatus, and means for operating said movable member.

7. A cleaning apparatus comprising, a bed adapted to receive an object to be cleaned, a resilient and automatically adjustable abutment for said object, a movable member to force said object against said abutment, a vibrator mechanism to produce vibrations in said apparatus, and means for operating said movable member; said abutment comprising, a wall provided with a conical opening, an abutment stool having a stem guided in the small end of said conical opening and a head on one end of this stem, and a spring over said stem and between said head and said wall.

8. A cleaning apparatus comprising, a bed adapted to receive an object to be cleaned, two abutments for said object, a slide engaging said object substantially midway of and opposite said abutments, means for operating said slide, and means for producing vibrations in said apparatus.

9. A cleaning apparatus comprising, a bed adapted to receive an object to be cleaned, an abutment for said object on one end of said bed, a slide on said bed to force said object against said abutment, a cylinder on the other end of said bed, a piston in said cylinder, a piston rod connecting said piston and said slide, and means for producing vibrations in said apparatus.

10. A cleaning apparatus comprising, a bed adapted to receive an object to be cleaned, an abutment for said object on one end of said bed, a slide on said bed to force

said object against said abutment, a cylinder on the other end of said bed, a piston in said cylinder, a piston rod connecting said piston and said slide, and a vibrator mechanism on said slide.

11. A cleaning apparatus comprising, a bed adapted to receive an object to be cleaned, an abutment for said object on one end of said bed, a slide on said bed to force said object against said abutment, a cylinder on the other end of said bed, a piston in said cylinder, a piston rod connecting said piston and said slide, a fluid pressure vibrator on said slide, and a source of fluid pressure for said cylinder and said vibrator.

12. A cleaning apparatus comprising, rigid means for supporting an object to be cleaned, resilient means for abutting one side of said object, movable means for holding said object down on said rigid means and against said resilient means, and a fluid pressure vibrator mechanism acting on said movable means to produce vibrations in said rigid means and in said movable means.

13. A cleaning apparatus comprising, means for holding an object to be cleaned unyieldingly in one direction and resiliently in another direction, and means for producing vibrations in said holding means.

14. A cleaning apparatus comprising, means for holding an object to be cleaned unyieldingly in one direction and resiliently in another direction, means for producing vibrations in said holding means, and means for transmitting said vibrations to said object in more than one direction.

JOHN T. STONEY.
